TELEGRAPH TRANSMITTER

Alfred Lahl, Frankfort-on-the-Main, Germany,
assignor to Telefonbau und Normalzeit Akti-
engesellschaft, Frankfort-on-the-Main, Ger-
many, a corporation of Germany

Application December 29, 1936, Serial No. 118,100
In Germany December 31, 1935

12 Claims. (Cl. 178—79)

This invention relates to keyboard telegraph instruments having permutation members which are selectively displaced by depression of the keys and having a motor driven cam assembly, the cams of which are set in accordance with the setting of the permutation members. The cams remain set during rotation of the assembly and act upon a transmitting contact, thus causing the emission of a signal determined by the key which was depressed. In the instruments with which the invention is concerned, the permutation members are spring loaded, that is to say, they are normally under the action of springs by means of which they are displaced on depression of a key.

If, in an instrument of the above kind, a second key is depressed before the transmission of the signal determined by the depression of the first key has been completed, another set or combination of permutation members is displaced and, unless the second key is held depressed until the transmission of the first signal is completed and the cams have been re-set, an incorrect signal is transmitted.

The object of the invention is to overcome the necessity for keeping the second key depressed in instruments of the above kind having spring loaded permutation members.

This object is achieved in accordance with the invention by providing an auxiliary mechanism which is set in the operative position by the depression of a key and which holds the intermediate members in the position in which they are set by a key independently of the position of that key until the setting of the contact actuating cams in accordance with the setting of the intermediate members has been completed.

The invention thus makes it possible for two keys to be struck in quick succession and to be released again during the time in which the current impulse sequence selected by the first key is still being sent out, without endangering the correct transmission of either of the impulse sequences. By means of the auxiliary mechanism, the impulse sequence selected by the second key is stored up in the intermediate members while the signal sequence selected by the first key and stored up in the contact actuating members is being sent out. When, at the end of the revolution made by the contact actuating members, the latter are returned to their normal position, they are automatically caused to make a further revolution owing to the new setting of the intermediate members which has already been effected and which is maintained independently of the

maintenance or non-maintenance of the key in the depressed position. A further key can then be struck during the transmission of the second current impulse sequence.

In order that the invention may be properly understood and be more readily carried into effect, an example of construction in accordance therewith will now be described with reference to the accompanying drawings, in which

Figures 1 and 1A show diagrammatically and in perspective a part of the telegraph transmitter in the normal and in the operated position respectively.

Figures 2 and 2A show diagrammatically and in perspective in the normal and in the operated positions the distributor of the transmitter and the means which form the auxiliary device provided in accordance with the invention.

Figure 3 shows a detail of Figures 1 and 1A to a larger scale.

Figure 4 is an end view to a larger scale of the distributor of Figure 2 showing the various cams, and

Figure 5 is a development of these cams shown in Figure 4.

Only one key, the key A of the telegraph transmitter, is shown. This key is pivotally mounted on a pin 1 and, in the normal position (Fig. 1) is pressed against a bar 2 by a spring 3 held in the clamp 4. The rear part of the key lever extends beneath the teeth of the permutation members a—e and beneath a rail 5. The permutation members a—e are mounted for movement on the rods 6 and 7. Each of them is provided with a spring 8. In the normal position (Fig. 1), the permutation members a—e lie with their upwardly projecting lugs 9 abutting against a common stop rail 10. This stop rail 10 is pivotally mounted on the rod 11 and, in the normal position, is locked against movement by the catch 12 which is pivotally mounted on the pin 13 and, in the position under consideration, is supported by the lug 14 on the rail 5 which engages beneath its arm 15. The lug 14 (Figure 3) is pivotally attached to the rail 5 which is itself pivotally mounted at 16. On depression of the key A, the rail 5 is swung upwards about its pivot 16 against the action of its spring 17 so that the arm 15 of the catch 12 is lifted by the lug 14. The lug 14 eventually comes clear of the arm 15 so that the catch 12 can, if desired, return to its normal position under the action of the spring 18 even if a key is still depressed. The catch 12 releases the stop rail 10 so that it can turn on its pivot pin 11 under the action of the spring 19 and the

- permutation members *a*—*e* can move under the action of their springs 8 in so far as they are not restrained from so doing by their teeth coming against the arm 20 of the key lever (Fig. 1A). 5
- On release of the depressed key, the rail 5 resumes the position shown in Figure 1 without moving the catch 12, the lug 14 being pressed back against the action of its spring 21 (see Figure 3). 10
- 10 A signal corresponding to the depressed key is emitted through the agency of a rotary distributor of the type of that shown in U. S. Patent No. 1,983,960 of Max Amann. This distributor comprises a rotatable shaft 22 carrying at one 15 end a set of movable cams 23*a*—23*e* which act on the transmitting contact 24 through the lever 25 (Figure 2).
- The cams 23*a*—23*e* are slidably mounted in a block 26 on the shaft 22 and can be moved 20 outwards therethrough parallel to the shaft 22 by the compression springs 27*a*—27*e* acting through the axially displaceable rods 28*a*—28*e*. The rods 28 are, however, in the normal position, kept back by locking discs 29*a*—29*e* through 25 bayonet slot connections 30. The discs 29 are mounted for rotation on the shaft 22 and can be turned through a small angle against the action of the springs 31 (only one is shown in Figure 2), in order to release one or another of the rods 28. For producing this rotation of the discs 29 relatively to the shaft 22, a series of unlatching levers 32*a*—32*e*, one for each permutation member, is provided, the noses 33 of which normally lie in the path of movement of the noses 34 on 30 the discs 29 when the shaft 22 is rotated. The levers 32 remain in the normal position illustrated in Figure 2 as long as the permutation members remain in the normal position. When, however, a permutation member moves forward, the member *c*, for example, as shown in Figure 2A, the associated lever 12 is swung back by the abutment against the tail of the permutation member with its nose 33 clear of the associated disc 34. Consequently, during the early part of the 35 rotation of the shaft 22, the levers 32 which remain in the normal position strike the noses 34 on the discs 29 associated with them so that the latter are thus turned relatively to the shaft and the rods 28 associated with them are released and, under the influence of their springs 27, displace 40 the associated contact operating cams 23 out of the block 24. The levers 32 are resiliently connected to the associated permutation members *a*—*e* by springs 35 and upon further rotation of the shaft 22, the levers 32 are pushed back by 45 the discs 29, the latter then being compelled to share in the rotation of the shaft. During the rotation of the shaft 22, the cams 23 which have been pushed out of the head 26 by their springs 50 actuate the contact 24 through the lever 25. The shaft 22 is driven at appropriate times by a constantly rotating hollow shaft 36 through a clutch formed by the ratchet wheel 37 which is fixed to the shaft 36 and the pawl 38 which is 55 pivotally mounted on a cam disc 39 fixed to the shaft 22. For the sake of clearness, the ratchet wheel 37 and the pawl 38 have been shown at the front of the cam disc 39. They should, of course, in order that the ratchet wheel may be fixed to the shaft 36, be at the back of the cam disc. In the normal position, the clutch pawl 38 is held 60 out of engagement with the ratchet 37 by a pawl 40 against the action of its spring 41, the pawl 39 being held in position against the action of its spring 42 by an arm 43 of the stop rail 10.

When the stop rail is pivoted, the arm 43 is moved so that the pawl 40 is pulled back by the spring 42 and the pawl 38 can engage with the ratchet wheel 37 and cause the shaft 22 to rotate with the shaft 36 (Fig. 1A). The tail 44 of the pawl 5 39 is thus brought into a position in which it can be acted upon by the cam 45 on the cam disc 39 and is brought back into the position shown in Fig. 1 in which it will provide an abutment for the clutch pawl 39 when the latter comes round again. 10 The stop rail 10 is connected by a connecting rod 46 to a stirrup 47 which is pivotally mounted at 48. Shortly after the beginning of the rotation of the shaft 22, the stirrup 47 is pivoted by the cam 49 on the head 26 and the connecting rod 15 46 returns the stop rail 10 and the permutation members abutting against it from the position of Fig. 1A into the normal position shown in Fig. 1. When the rail 10 is swung by its spring 19 its arm 43 also acts upon a two armed lever 50 (Figure 2) which serves for the simultaneous operation of five hooks 51*a*—51*e* associated with the levers 32*a*—32*e*. These hooks 51 have elongated holes 52 in them by means of which they are arranged in a row on a rod 53. They are pressed 25 towards the associated levers 32 by the teeth of a comb-like leaf spring 54 in the normal position. They do not however, touch the levers 32 or restrict their pivotal movement. The hooks 51 are guided in holes in a rail 55 which is pivotally 30 mounted on the rod 53. When the arm 43 is lifted, the lever 50 is swung clockwise so that its right hand arm (Figs. 2 and 2A) lowers the rail 55 and the hooks 51 against the action of the spring 56. The hooks 51 are thus brought either 35 behind the associated levers 32 or into the grooves 57 of these levers, according as the levers in question are in their normal position or in their actuated position.

The arrangement described above operates as 40 follows: On depression of the key A, the arm 20 of the key lever is lifted against the action of its spring and enters a space between two successive teeth of the permutation members *a*—*e*. On complete depression of the key, the arm 20 45 pivots the rail 5 and this, in turn, through the lug 14, swings the latch 12 which, up till now, has been holding the stop rail 10 against movement. The stop rail 10 being thus released, those of the permutation members *a*—*e* which are not 50 held back by the arm 20 are moved by their springs 8 to the right and swing the levers 32 associated with them out of the path of movement of the locking discs 31.

The stop rail 10 is swung on its pivot pin by the 55 permutation members and by its spring 19 so that the arm 43 is lifted and the pawl 40 released. Under the pull of its spring 42, the pawl 40 swings counterclockwise and releases the clutch pawl 38 which is caused by its spring 41 60 to engage with the constantly rotating ratchet wheel 37. The shaft 22 is thus clutched to the shaft 36 and is rotated thereby together with the rods 28, the discs 29 and the contact operating cams 23 and the control cams 45 and 49.

For the purpose of illustration, it will be assumed that on depression of the key A, only the permutation members *b*, *c*, *d* are moved, the members *a* and *e* being held back by the arm 20. In that case, the levers 32*b*, 32*c*, and 32*d* are displaced while the levers 32*a* and 32*e* remain in the path of movement of the locking discs 29. When the arm 43 rises, the lever 50 is swung clockwise and the rail 55 is lowered together with the hooks 51. The hooks 51*b*, 51*c* and 51*d* are thus brought into 70 75

the grooves 57 in the levers 32b, 32c and 32d (as shown in Fig. 2A, for the lever 32c) while the hooks 51a and 51e come opposite the backs of the levers 32a and 32e. As long as the rail 55 remains depressed, the levers 32b, 32c, 32e are held by the associated hooks 51 independently of the position of the permutation members. The key A can therefore be released. Shortly after the beginning of the rotation of the shaft 22, the noses 34 on the discs 29a and 29e strike the levers 32a and 32e. These two discs and only these two are therefore held back by their corresponding levers 32 and, in consequence of the rotation of the shaft 22, are displaced against the action of their springs 31. The rods 28a and 28e are thus released and under the influence of their springs are moved axially and push out the contact operating cams 23a and 23e. On further rotation of the shaft 22, the momentarily stopped discs 29a and 29e are carried round and the levers 32a and 32e are pressed back against the action of their springs 35.

When the shaft 22 is at rest, the lever 25 is pressed against the cam 58 which is an immovable part of the head 26, by the spring 59. During the first part of the rotation of the shaft 22 the lever 25 slips off the cam 58 so that the transmitting contact 24 sends out the start impulse. This occurs during the first $\frac{1}{4}$ th of the revolution made by the shaft 22. During each of the next five $\frac{1}{4}$ ths of the revolution of the shaft 22, the lever 25 is actuated by one or another of the cams 23. As, in the case under consideration, only the cams 23a and 23e are pushed out from the head 26, the lever 25 remains, during the 3rd, 4th and 5th sevenths, in the position assumed for the sending out of the start impulse, but is shifted by the cams 23a and 23e during the 2nd, and 6th sevenths into the normal position shown in Figure 2, in which position it is held by the fixed cam GS during the last seventh.

During the first $\frac{1}{4}$ th of the revolution made by the shaft, the cam 45 strikes the tail 44 of the pawl 40 (Figures 1 and 4) and swings the latter against the action of the spring 42 into its normal position in which it lies in the path of movement of the head of the clutch pawl 38. Shortly following this, say during the 2nd 7th of the rotation, the cam 49 swings the stirrup 47 (Figures 1 and 2) which, through the connecting rod 46, restores the stop rail 10 and the permutation members to their normal positions. This brings the arm 43 again in front of the pawl 40 so that the latter is held fast. As the lug 14 (Figure 3) at the end of its movement, bears laterally against the arm 15 of the catch 12, it is now free to move even if, at this instant, the key A is still depressed. The catch 12 locks the stop rail 10 again in its normal position. If the key A is subsequently released, the lug 14 will again come under the arm 15 as it returns into the normal position.

During the restoration of the stop rail 10 to the normal position, the lever 50 is also released by the arm 43. The rail 55 is then lifted by the spring 56 and the hooks 51b, 51c and 51d release the associated levers 32 so that the latter and the displaced permutation members return to their normal positions.

The restoration of the permutation members and of the levers 32 is effected during the first half of the revolution made by the shaft 22. The selected current impulse series is nevertheless correctly sent out because the discs 29 and

the contact actuating cams 23 have already been set for that series. The cams 23 are re-set after they have acted on the lever 25 by means of a re-setting member (not shown) which, when one of these cams is brought opposite it, pushes it back through the discs 29 against the action of the springs 27. The discs 29, under the influence of their springs 31, then spring into their normal positions in which they lock the cams in the inoperative position. At the end of the revolution of the shaft, the clutch pawl 38 strikes the head of the pawl 40 so that it is brought out of engagement with the rotating ratchet wheel 31 and the shaft is de-clutched.

If another key is struck during the rotation of the shaft 22 and after the return of the permutation members, say at the beginning of the second half of the revolution, the permutation members are again released so that, in the manner already described, those of the levers 32 which are associated with permutation members which are not held back by the arm 20, are swung out of the path of movement of the discs 29. The rail 55 and the hooks 51 are lowered by the lever 50 so that the levers 32 are locked in the positions they at that instant occupy. The newly struck key can now be released—even before the first revolution of the shaft 22 is completed. The levers 32 are held locked by the hooks 51 until at the beginning of the second revolution of the shaft 22, the discs 29 and the contact actuating cams 23 have been set again in accordance with the setting of the levers. It is only then that the permutation members and the levers 32 are returned by the cam 49 and the stirrup 47. When the second key is struck, the pawl 40 is released so that the clutch pawl 38 is not disengaged at the end of the first revolution. The clutch thus remains closed and the second revolution follows immediately on the first.

I claim:—

1. A telegraph transmitter comprising a plurality of operating keys, a transmitting contact, a motor, a rotatable body, a clutch device controlled by said keys for coupling said body to said motor for the duration of one revolution, movable cams carried by said body for influencing said transmitting contact on rotation of said body, a plurality of spring-loaded permutation members selectively releasable for displacement by their springs on actuation of said keys, a plurality of intermediate members adapted to be set by said permutation members whereby to set said movable cams at the beginning of each revolution of said rotatable body, means for locking said intermediate members in the set position, means responsive to the depression of a key for bringing said locking means into operation and means adapted to be influenced by said rotatable body after said movable cams have been set by said intermediate members for making said locking means inoperative, said last mentioned means being independent of the depression of an operating key.

2. A telegraph transmitter comprising a set of operating keys, a transmitting contact, a motor, a rotatable body, a clutch device controlled by said keys for coupling said body to said motor for the duration of one revolution, movable cams carried by said body for influencing said transmitting contact on rotation of said body, a plurality of spring-loaded permutation members selectively releasable for displacement by their springs on actuation of said keys, a set of intermediate members connected to said per-

mutation members for setting said movable cams at the beginning of each revolution of said rotatable body in accordance with the setting of said permutation members, means controlled by said permutation members during their movement determined by said keys for locking said intermediate members in the set position, and means controlled by said rotatable body for releasing said locking means after said cams have been set, said releasing means being independent of the depression of an operating key.

3. A telegraph transmitter according to claim 1 in which each of said intermediate members comprises a notch and said locking device comprises a plurality of locking members, one for each intermediate member and adapted to be engaged in said notches of said intermediate members.

4. A telegraph transmitter comprising a transmitting contact, a motor, a rotatable body, a clutch device for coupling said body to said motor for the duration of one revolution, movable cams carried by said body for controlling said transmitting contact on rotation of said body, means carried by said body for locking and unlocking said movable cams, a set of operating keys, a plurality of spring-loaded permutation members selectively releasable by their springs on actuation of said keys, a set of intermediate members adapted to be set by said permutation members on movement of said permutation members in one direction, springs connecting said intermediate members individually to said permutation members, said cam locking and unlocking means comprising stops, said intermediate members being adapted at the commencement of the rotation of the rotatable body to act on said stops for setting said cam locking and unlocking means in accordance with the setting of said permutation members responsive to the depression of said keys for locking said intermediate members in the set position against movement by said springs and means actuated by said rotatable body after the actuation of said cam locking and unlocking means by said intermediate members for returning said locking device, said returning means being independent of the depression of a key, said intermediate members comprising notches and said locking device comprising hooked members one for each intermediate member, said hooked members being adapted to engage in said notches.

5. A telegraph transmitter according to claim 4, in which said hooked members are mounted for rotation and for translation, and comprising springs acting upon said hooked members to resist translation thereof and guide bar adapted to turn said hooked members into and out of engagement with said notches.

6. A telegraph transmitter according to claim 4, in which said locking means comprise a guide bar, guide passages in said guide bar one for each of said hooked members, said hooked members being mounted for rotation and for translation, a comb-like spring common to all said hooked members adapted to resist translation of said members, said guide bar being adapted to turn said hooked members respectively into and out of engagement with said notches under the influence of an operating key and under the influence of said returning means.

7. A telegraph transmitter comprising a transmitter contact, a motor, a rotatable body, a clutch device for coupling said body to said motor for one revolution of said body, movable cams carried by said body for controlling said transmitter

contact on rotation of said body, springs acting upon said cams, discs carried by said body for locking and unlocking said cams, each one of said discs influencing a different one of said cams, said discs being mounted for rotation about the axis of said body, a plurality of springs each adapted to hold a different one of said discs in a position for locking the cam associated with it, a set of operating keys, a set of permutation members controlled by said keys, a set of intermediate members connected to said permutation members and adapted to set said cams in accordance with the setting of said permutation members, stops on said discs adapted to be influenced against the action of said springs by said intermediate members at the beginning of the rotary movement of said body, said discs when thus influenced being turned to release the corresponding cams for movement under the action of said springs, a device for locking said intermediate members in the position in which they are set by said permutation members, said locking device embodying hooked members mounted for rotation and for translation, each of said hooked members being adapted to lock one of said intermediate members, a controlling bar for turning said hooked members into their locking position, springs acting upon said hooked members adapted to resist translation of said members, said springs being stronger than said springs acting upon said discs and therefore preventing a movement of an intermediate member locked by its hooked member when a disc on being influenced by said intermediate member is turned against the action of its spring, means responsive to the depression of a key for actuating said controlling bar of said locking device, means actuated by said rotatable body after the actuation of said discs by said intermediate members for returning said controlling bar, said returning means being independent of the depression of a key.

8. A telegraph transmitter according to claim 7, comprising springs acting upon said permutation members in their normal position, means for locking said permutation members against the action of said springs, means for releasing such locking by actuation of said keys and means for returning said bars to their normal position, said last mentioned returning means being actuated by said rotatable body on its being rotated.

9. A telegraph transmitter according to claim 7 comprising springs acting on said permutation members in their normal position, a movable pawl acting upon all said permutation members, means for locking said pawl, means for releasing said locking by actuation of said keys, said pawl being connected to said returning means actuated by said rotatable body.

10. A telegraph transmitter according to claim 7, comprising springs acting upon said permutation members in their normal position, said permutation members being provided with projections and recesses adapted to cooperate with the said keys, a movable pawl for locking said permutation members against the action of said springs, means for locking said pawl, a bar adapted to be influenced by said key, a lug on said bar adapted to move said locking means out of the locking position, said last mentioned bar being actuated by said keys after their engagement with said permutation members, said pawl being connected to said returning means actuated by said rotatable body.

11. A telegraph transmitter comprising a transmitting contact, a motor, a rotatable body, a clutch device carried by said body for coupling said body to said motor, movable cams carried by said body for controlling said transmitting contact, movable means carried by said body for setting said cams, a plurality of operating keys, a plurality of permutation bars, spaced teeth on said permutation bars, recesses adapted to cooperate with said keys, springs acting on said permutation bars in their normal position, a movable pawl for locking said permutation bars against the action of said springs, means for locking said pawl, a further bar adapted to be influenced by said keys after their engagement with said permutation bars, a lug on said further bar adapted to move said locking means out of the locking position, a plurality of intermediate members adapted to be set by said permutation bars and thereby to set said cam setting means, stops on said cam setting means of said rotatable body which at the beginning of the rotary movement

of said body are influenced by said intermediate members, hooked members for locking said intermediate members in the set position, means actuated by said pawl for controlling said hooked members, means actuated by said pawl for actuating said clutch device, means actuated by said rotatable body on its rotary movement shortly after the actuation of said cam setting means by said intermediate members for turning said pawl into its locking position, a spring acting upon said means for locking said pawl, said means being adapted to lock said returned pawl independently of the position of the key depressed to unlock said pawl. 5 10

12. A telegraph transmitter according to claim 11, in which said lug is movably mounted on said bar and is adapted after having moved said means for locking said pawl out of locking position on depression of a key to release said locking means for movement into its locking position 20 when said pawl has been returned. 15

ALFRED LAHL.
